(57) **CLAIM**

The ornamental design for a load back rest for a lift truck, as shown and described.

DESCRIPTION

FIG. 1 is a front isometric view of a load back rest for a lift truck, showing my design;

FIG. 2 is a rear isometric view thereof;

FIG. 3 is a front elevational view thereof;

FIG. 4 is a rear elevational view thereof;

FIG. 5 is a right side elevational view thereof, the left side elevational view being a mirror image of the right side view;

FIG. 6 is a top plan view thereof; and,

FIG. 7 is a bottom plan view thereof.

The broken line showing in the drawings is included for the purpose of illustrating portions of the load back rest for a lift truck and forms no part of the claimed design.
